UNITED STATES PATENT OFFICE

HENRY F. BOILLOT, OF MARSHALL, MISSOURI, ASSIGNOR OF ONE-HALF TO GLENN S. NOBLE, OF CHICAGO, ILLINOIS

SELF-IGNITING CIGARETTE

Application filed January 22, 1930. Serial No. 422,620.

This invention relates to self-igniting cigarettes, and an object of the invention is to provide a striking head on the end of a cigarette which when drawn across a friction surface on the cigarette package will indirectly cause the tobacco filler to burn.

Another feature of the present invention is to provide a combustible disk between the striking head and the tobacco filler which will be of slow burning nature to insure the entire area of the tobacco filler, becoming ignited after the striking head has burned.

Another feature of the present invention is to provide a deflagrating adhesive about the edges of the disk, that not only secures the disk to the wrapper of the cigarette but progressively burns about the periphery of the disk so as to insure complete combustion of the disk and economize in the amount of material used in the striking head.

Another feature of the invention is to provide a disk of the character referred to that will not allow the taste of any of the products of combustion of the striking head to permeate the tobacco and which is non-poisonous, that burns without odor, and is entirely tasteless.

Further objects of the invention are to provide, in a manner as hereinafter set forth, a cigarette of the character referred to that is very simple in its method of assembly, thoroughly reliable for its intended purpose, having added utility without marring the appearance thereof, that is strong, compact and durable, and that is comparatively inexpensive to manufacture.

With the foregoing and other objects in view, the invention consists of a novel construction, combination and arrangement of parts as will be hereinafter more specifically described and illustrated in the accompanying drawings, wherein is disclosed an embodiment of the invention, but it is to be understood that changes, variations, and modifications may be resorted to without departing from the spirit of the claims hereto appended.

In the accompanying drawings:

Figure 1 is a perspective view of a cigarette package, partly broken away, and in accordance with the present invention,

Fig. 2 is a perspective view of a cigarette formed in accordance with the present invention,

Fig. 3 is a vertical diametric section through the cigarette,

Fig. 4 is an enlarged fragmentary, diametric section at the upper end of the cigarette, and

Fig. 5 is a perspective view of the pliant fibrous disk forming a part of the present invention.

Referring to the drawings in detail, 6 indicates generally a package of cigarettes having a striking surface 7 on one side thereof. This striking surface 7 is similar in all respects to the striking surface of a match box preferably intended for safety matches.

The cigarette of the present invention includes a tobacco filler 8 confined in a tubular wrapper 9 that may be of paper or the like. Anchored in one end of the tubular wrapper 9 so that its outer face is approximately flush with the upper edges of the tube, is a pliant, fibrous disk 10 preferably formed of blotting paper or other suitable absorbent material.

It will be apparent, that since the fibrous disk is pliant, that there is no possibility of breaking this disk during the packing or storage of the cigarettes. Furthermore, 80 since the disk is fibrous in nature, it is porous and may permit a draft of air being drawn therethrough if the smoker draws on the cigarette before the disc is consumed, but ordinarily the disc is burned almost instantaneously.

Prior to the insertion of this disk 10 in the upper end of the tubular wrapper, it is soaked in saltpeter and dried so as to insure the burning of the disc over its entire area 90 once it has been ignited.

The inner face of the disk 10 is in contact with or in abutting relation to the outer end of the tobacco filler 8, so that the burning of the disk will ignite the tobacco filler. The 95 peripheral edge of the disk is coated with a deflagrating or easily combustible adhesive, by means of which the disk is secured to the inner wall of the tubular wrapper 9 at the end thereof.

This deflagrating adhesive is indicated at 11, and consists of glue mixed with a proportion of saltpeter that is sufficient to give the deflagrating properties thereto. I prefer to use a glue or adhesive which will not have an objectionable odor or taste when it is burned, as for instance, dextrin or other suitable vegetable compound.

The cigarette is provided with a striking head 12, that is adapted to be frictionally moved across the strip 7 to ignite the same similarly to the means of igniting safety matches. This striking head 12 is placed in position to light the disc and adjacent parts and is preferably only contiguous with a portion of the circumference of the disk 10, and is preferably formed on one-half the area of this disk.

It will be understood that the striking head 20 is deposited on the end of the cigarette in the plastic state in any suitable manner, whereby it adheres to and anchors itself to the fiber of the disk or to the disc and adjacent portion of the wrapper.

25 In the application of the present invention, the head 12 is struck on the strip 7 whereupon this head bursts into flame. The flame causes the disk 10 to burn in the area on which the head is supported. At the 30 same time, the deflagrating adhesive layer 11 about the periphery of the disk is ignited and progressively burns about the entire periphery of the disk, insuring that the disk will burn over its entire area.

35 It will be understood that the disk being of a fibrous nature, will burn slower than the head or the deflagrating adhesive. While the adhesive seals the upper end of the tube 9, it is also secured to the upper portion of 40 the tube. It therefore follows that when the deflagrating adhesive burns, it will also ignite the upper end of the wrapper, which insures a most perfect combustion of the entire area of the tobacco filler at the upper 45 end of the tube.

Since the fibrous disk is odorless, tasteless and non-poisonous, it will be apparent that any fumes of combustion from the head 50 12 will not permeate the tobacco filler, because the head 12 is completely burned before the burning disk 10 ignites the tobacco filler.

It is to be understood that by describing in detail herein any particular form, structure, or arrangement it is not intended to limit the invention beyond the terms of the several claims or the requirements of the prior art.

Having thus described my invention, what 55 I claim as new is:—

1. A self-igniting cigarette including a tobacco filler and a wrapper, comprising a fibrous combustible disk at one end of the wrapper, deflagrating adhesive on the edge 60 of the disk for securing the latter to the

wrapper, and an ignition head on the outer face of the disk to ignite the disk and the wrapper.

2. A cigarette comprising a tubular wrapper, a filler in said wrapper, a paper disc for closing one end of the wrapper which is secured thereto by an adhesive comprising glue mixed with sufficient saltpeter to form a rapidly combustible adhesive and a striking head applied to the closed end of the cigarette, which head is adapted to be ignited by friction on a suitable surface.

In testimony whereof I affix my signature.

HENRY F. BOILLOT.
